(57) **CLAIM**

The ornamental design for a frozen dessert pop, as shown and described.

DESCRIPTION

FIG. 1 is a perspective view of a frozen dessert pop showing our new design;

FIG. 2 is a front elevational view thereof;

FIG. 3 is an elevational view thereof from one of its side faces;

FIG. 4 is an elevational view thereof from a second of its side faces;

FIG. 5 is an elevational view thereof from a third of its side faces;

FIG. 6 is a top plan view thereof;

FIG. 7 is a bottom plan view thereof;

FIG. 8 is a second embodiment of a frozen dessert pop showing our new design;

FIG. 9 is a front view thereof;

FIG. 10 is an elevational view thereof from one of its side faces;

FIG. 11 is an elevational view thereof from another of its side faces;

FIG. 12 is an elevational view thereof from a third of its side faces;

FIG. 13 is a top plan view thereof; and,

FIG. 14 is a bottom plan view thereof.
